UNITED STATES PATENT OFFICE.

HENRY EDWIN PARSON, OF NEW YORK, N. Y.

AUTOMATIC BOILER-PRESSURE REGULATOR.

SPECIFICATION forming part of Letters Patent No. 784,121, dated March 7, 1905.

Application filed November 18, 1903. Serial No. 181,722.

To all whom it may concern:

Be it known that I, HENRY EDWIN PARSON, a citizen of the United States of America, and a resident of and post-office address being 320 5 Broadway, New York city, State of New York, have invented certain new and useful Improvements in Automatic Boiler-Pressure Regulators, of which the following is a specification.

This invention relates to improvements in 10 an automatic boiler-pressure regulator used, primarily, in the automatic boiler-pressure regulator shown in my Patent No. 742,128, bearing date of October 20, 1903.

The object of my invention is to provide an 15 automatic valve structure which will operate with as little friction as possible when a desired change of boiler-pressure occurs and yet be insensible to minute changes of boiler-pressure due to engine pulsations, the object being 20 to maintain the steam-pressure in the boiler as nearly uniform as possible.

A further object of the invention is to employ a diaphragm, a valve, and a stem connecting these two elements, the means employed for coupling the stem being arranged 25 in such manner as will permit of a slight displacement of the alignment of the diaphragm and yet not bind the valve in its case and prevent its free movement.

30 The invention also comprehends improvements in the specific details of construction and arrangement of parts whereby I am enabled to produce a compact, durable, and neat construction, as well as one which can be conveniently dismantled for the repairing of the 35 parts.

In the drawings, Figure 1 is a vertical section of my improved regulating-valve. Fig. 2 is a central transverse section of the same. 40 Fig. 3 is a detail bottom plan view. Fig. 4 is a detail vertical section taken through the weighted lever. Fig. 5 is a detail top plan view of the valve. Fig. 6 is a horizontal section on the line 6 6 of Fig. 1.

45 The same numerals refer to like parts in all the figures, wherein 1 represents a hollow base, in which is mounted the weighted lever 2. The lever 2 is fulcrumed at 3 and has formed at one end a V-shaped notch 4, while 50 at its opposite end a weight 5 is suspended.

A valve-casing 6 is fastened to the top of

the base 1 by screws 7, and between the said casing and the base is clamped a diaphragm 8. Clamps 9 and 10 impinge on the diaphragm, and they are held together by the threaded 55 end 11 of a bolt 12. The clamp 10 has a hollow reduced depending projection 13 to receive a hardened block 15, provided on its under side with a knife-edge 16, which fits in the V-shaped notch 4. The notch is somewhat wider than the body of the knife-edge to permit of the lever being rocked without binding the parts.

The bolt 12 is square, as shown in Fig. 6, except that its corners are cut off and ground 65 to a circle, so as to fit into and be guided by the cylindrical casing 6. The square bolt 12, fitted within the circular casing 6, leaves steam-passages surrounding the bolt and communicating between the casing 6 and the upper 70 side of the diaphragm 8. In the top of the bolt 12 there is a circular opening 16^a, and through the bolt there is also a horizontal hole 17, which enters the circular hole 16. Within the vertical hole 16 is located a nut 75 18, which fits loosely therein, and through the lower end of which and through the bolt there passes a pin 19.

The valve 24 (shown in plan in Fig. 5) is mounted to vertically reciprocate against a 80 seat 26, formed on the inner wall of the upper part of the casing 6. The valve is formed with a ground face 27, having a vertical groove 28, and on the opposite side there is a vertical groove 28^a, extending from the top 85 to the bottom of the valve, while its sides opposite the face 27 are cut away to form steam-passages around the valve and to maintain the valve upon its seat by steam-pressure. A screw 29, having a reduced end 30, is 90 tapped into the side of the extension 6^a, the said extension entering the notch 28^a, which prevents the valve being turned.

An inlet-opening 33 is formed in the side of the casing 6, and through this opening steam 95 is admitted from the boiler to act on the diaphragm. Beyond the valve-seat 26 the casing 6 has a projection 35, provided with a channel 36, leading to a main operating-valve, (not shown,) and in the same projection and adjacent the channel 36 is another channel, 38, which communicates with an exhaust-pipe.

Steam enters the opening 33 and acting on the diaphragm depresses the end of the lever and rocks the latter on its fulcrum 3.

As the lever is rocked under the influence 5 of the steam-pressure, as clearly pointed out in the before-mentioned patent, obviously the apex of the V-shaped notch will move in the arc of a circle of which the pivot 3 is the center, and as the knife-edge 16 rests therein 10 it will likewise follow the same arc. The edges of the diaphragm being fixed and the knife-edge traveling in the arc of a circle, the axis of the bolt 12 is thrown out of the perpendicular, and were it not for the loose connection 15 between the rod 22, the bolt 12, and the valve 24 the latter would bind with every motion of the diaphragm. In other words, the connections between these members form a universal joint which allows the valve to 20 freely and positively move in contact with its seat irrespective of any unusual twist or tilting of the diaphragm. The diaphragm having descended, it follows that the top of 25 the valve will uncover the port 36, which admits boiler-pressure to the main valve. (Not shown.) When the boiler-pressure declines in consequence of more steam being used than is being generated, the weight 5 will force 30 the diaphragm upward against the steam-pressure and raise the valve 24 so as to close the channel 36 with the valve. As the pressure continues to decline by the excessive use of steam the weight 5 will raise the diaphragm 35 above its horizontal position and raise the valve 24 until the groove 28 is brought to register with both the channels 36 and 38 and form a communicating channel between them.

The nicety of adjustment at the point of contact between the knife-edge 16 and the V-shaped groove 4 serves to prevent undue friction 40 at this point and insures the slightest movement of the weighted lever being communicated to the valve. Furthermore, the connection between the valve and the diaphragm is such that any movement, from the minutest impulse to the severest blow due to 45 abnormal conditions of boiler-pressure, will not bind the valve, and thus prevent its free movement; nor is it absolutely necessary 50 that the two pins 17 and 23 be precisely positioned relative to the up-and-down movement of the lever 2 or that the end 30 of the bolt 29 fit its groove 28 accurately, since the universal connection will allow of any movement 55 between these parts. This feature is of the utmost importance in an apparatus of this type, as it serves the purpose of permitting quick and convenient assembling of the parts by unskilled workmen and amply affords 60 protection for free movement of the valve in case of wear or any undue jar.

Having thus described my invention, what I claim, and desire to secure by Letters Patent, is—

65 1. An apparatus of the class described, com-

prising a casing provided with inlet and outlet ports, and an exhaust-port, a valve adapted to move over the outlet and exhaust ports, and held against the ports by steam-pressure and adapted to establish communication between the interior of the casing and the outlet-port or between the outlet-port and the exhaust-port, a pressure-resisting means, means acting on the pressure-resisting means and actuated by boiler-pressure, and a universal connection between the means actuated by boiler-pressure and the valve, whereby the movement of the valve-actuating mechanism will have no tendency to lift the valve from its seat. 70

2. An apparatus of the class described comprising a casing provided with inlet and outlet ports and an exhaust-port, a valve adapted to move over the outlet and exhaust ports and held against the ports by steam-pressure and 75 adapted to establish communication between the interior of the casing and the outlet-port or between the outlet-port and the exhaust-port, a diaphragm actuated by boiler-pressure and a universal connection between said diaphragm and the valve whereby said diaphragm will have no tendency to lift the valve from its seat. 80

3. An apparatus of the class described comprising a casing having inlet and outlet ports 95 and an exhaust-port, a valve adapted to move over the outlet and exhaust ports and held against the ports by steam-pressure and adapted to establish communication between the outlet-port and interior of the casing or between the outlet-port and the exhaust-port, means actuated by boiler-pressure, mechanism connecting said means and the valve permitting the former to be moved at right angles to the axis of the valve without affecting the aligned movement of the valve, and means operating against the means actuated by boiler-pressure to resist said pressure. 100

4. An apparatus of the class described comprising a casing having inlet and outlet ports, 110 and an exhaust-port, a valve adapted to move over the outlet and exhaust ports and held against the ports by steam-pressure and adapted to establish communication between the interior of the casing and the outlet-port or between the outlet-port and exhaust-port, a lever, means actuated by the boiler-pressure which moves the lever, mechanism connecting said means and the valve permitting the means to be moved from a plane at right angle to the axis of the valve without affecting the desired movement of the valve. 115

5. An apparatus of the class described comprising a casing provided with inlet and outlet ports and an exhaust-port, a valve adapted to move over the outlet and exhaust ports and held against the ports by steam-pressure and adapted to establish communication between the interior of the casing and the outlet-port or between the outlet-port and exhaust-port, 125 130

means actuated by boiler-pressure and mechanism connecting said pressure-actuated means and the valve, permitting the pressure-actuating means to be moved in a plane at right angles to the valve without affecting the desired movement of the valve, a knife-edge formed on said pressure-actuating means, and a weighted lever provided with a notch in which said knife-edge fits.

6. An apparatus of the class described comprising a casing provided with inlet and outlet ports and an exhaust-port, a vertically-movable valve adapted to move over the outlet and exhaust ports and held against the ports by steam-pressure and adapted to establish communication between the interior of the casing and the outlet-port or between the outlet-port and the exhaust-port, means actuated by boiler-pressure, a knife-edge on said means, a universal connection between said means and the valve for permitting the means to tilt without affecting the vertical movement of the valve and a weighted lever provided with a notch into which the knife-edge fits.

7. An apparatus of the class described comprising a casing provided with inlet and outlet ports and an exhaust-port, a vertically-movable valve adapted to move over the outlet and exhaust ports and held against the ports by steam-pressure and adapted to establish communication between the interior of the casing and the outlet-port, or between the outlet-port and the exhaust-port, the valve being provided with a groove, a pin engaging the groove, a notch formed in the face of the valve, a diaphragm provided with a knife-edge, a rod between the valve and the diaphragm, a pin connecting the rod with the diaphragm and a second pin connecting the rod with the valve, said pins being arranged at right angles to each other, and a weighted lever provided with a V-shaped notch to receive the knife-edge.

8. In a regulator for steam-boilers, the combination with a casing having inlet and outlet ports and an exhaust-port, a valve adapted to move over the outlet and exhaust ports and held against the ports by steam-pressure and adapted to establish communication between the interior of the casing and the outlet-port, or between the outlet-port and the exhaust-port, means actuated by boiler-pres-

sure for moving the valve and a universal connection between said means and the valve.

9. In an automatic regulator for steam-boilers, the combination with a lever provided with means for depressing one of its ends, means actuated by boiler-pressure in one direction and connected to and actuated in the opposite direction by the lever, a casing provided with inlet and outlet ports and an exhaust-port, a valve adapted to move over the outlet and exhaust ports and held against the ports by steam-pressure and adapted to establish communication between the interior of the casing and the outlet-port or between the outlet-port and the exhaust-port, and a universal connection connecting the valve to the device actuated by boiler-pressure.

10. In an automatic regulator for steam-boilers, the combination with a pivoted lever, of means for depressing one end of the lever, a casing having inlet and outlet ports and an exhaust-port, a valve adapted to move over the outlet and exhaust ports and held against the ports by steam-pressure and adapted to establish communication between the interior of the casing and the outlet-port or between the outlet-port and the exhaust-port, a diaphragm in the casing, a connection between the lower side of the diaphragm and one end of the lever and a universal connection between the valve and the diaphragm.

11. A pivoted lever provided with means for moving one end thereof and provided at the other end with a transverse notch, a casing provided with inlet and outlet ports and an exhaust-port, a valve adapted to move over the outlet and exhaust ports and held against the ports by steam-pressure, and adapted to establish communication between the interior of the casing and the outlet-port or between the outlet-port and the exhaust-port, a flexible diaphragm actuated by steam-pressure in one direction, a knife-edge secured to the center of the diaphragm and standing in the notch of the pivoted lever and a universal connection between the diaphragm and the valve.

Signed by me at New York, N. Y., this 13th day of November, 1903.

HENRY EDWIN PARSON.
